HOUSING FOR AN ULTRA-VIOLET LAMP OR SIMILAR ARTICLE

Helmut Weissbrod and Günter Thomas, Hanau am Main, Germany, assignors to Quarzlampe Gesellschaft m.b.H., Hanau am Main, Germany

Filed Mar. 14, 1962, Ser. No. 69,252

Claims priority, application Germany Sept. 15, 1961

Term of patent 14 years

(Cl. D48—20)

FIG. 1

FIG. 2

FIG. 3

FIG. 5

FIG. 4

FIG. 1 is a side elevational view of a housing for an ultra-violet lamp or similar article showing our new design;

FIG. 2 is a bottom view thereof with the support in closed position;

FIG. 3 is a top view thereof with the support in closed position;

FIG. 4 is a front perspective view thereof; and

FIG. 5 is a rear elevational view thereof.

The dominant features of the design reside in the portions shown in full lines.

We claim:

The ornamental design for a housing for an ultra-violet lamp or similar article, as shown and described.
